UNITED STATES PATENT OFFICE.

WALTER HOH, OF LEIPZIG, GERMANY, ASSIGNOR TO THE FIRM HOH & HAHNE, OF LEIPZIG, GERMANY.

OSCILLABLE STAND FOR REPRODUCTION CAMERAS.

Application filed January 29, 1925, Serial No. 5,589, and in Germany March 19, 1924.

This invention relates to photographic copying apparatus and more particularly to the construction of supports or stands for such apparatus adapted to protect the apparatus from the effect of shocks transmitted through the floor of the building.

Shocks transmitted through the floor of the building are liable to cause relative movement between the parts of the photographic apparatus whilst exposures are being made and in order to prevent this it is usual to mount the apparatus on a rigid frame or girder supported by cushioning springs. So far as I am aware in all such known constructions one or more pairs of cushioning springs act on the frame or girder at opposite sides of the longitudinal axis thereof and I have found that such constructions are not entirely effective in preventing relative movement between the parts of the photographic apparatus as the members of each pair of springs yield unequally to vertical shocks and thus induce twisting strains in the frame or girder.

The object of the present invention is to provide an improved construction in which these twisting strains are avoided and according to the invention this is effected by supporting the frame or girder by springs which act on the frame or girder at points in the same containing the axis of the girder. In order that the single beam carrier be as strong as possible and possess greater resisting capability against twisting it is made of triangular cross section and constructed like a diagonally reinforced lattice girder.

I am aware that it has been proposed heretofore to provide photographic copying apparatus mounted on a rigid frame or girder supported by three vertically acting cushioning springs, one of which was disposed vertically under the axis of the girder. In this construction however, two of the cushioning springs were disposed at opposite sides of the longitudinal axis. According to the present invention all the supporting springs act on the frame or girder at points in the same vertical plane containing the axis of the girder.

An oscillable stand is shown by way of example on the accompanying drawings which mainly consists of a carrier of triangular cross section supported at the two ends

by two feet through the intermediary of one spring at each end.

Fig. 1 is a side elevation, and

Fig. 2 a front view of the reproduction apparatus.

Figs. 3 and 4 show modifications of the mounting and lateral guiding of the stand in front elevation.

The camera *a* and the drawing board *b* are carried by a girder *d* which is of triangular cross section stayed at all sides and resting upon two feet *g* through the intermediary of two springs *f*. The girder has vertical guide stays *h* parallel to one another at the points where it is to be mounted in the feet *g*, the two vertical stays at each end being mounted between rollers *i*. These rollers *i* are mounted on lugs which project laterally from the feet *g*. With the aid of the rollers *i* and by means of the vertical stays *h* the girder *d* is guided in the feet in accurately vertical direction. The two carriages *k* and *m* for the camera *a* and the drawing board *b* ride upon the girder and have rollers *n* which run on tracks on the upper edge of the girder *d*.

The drawing board may be illuminated by lamps *v* hanging from a frame *w*, of course somewhat at the side of the board so that said lamps do not impede the operation of the camera.

The girder *d* of triangular cross section may also be arranged so that its apex is turned down. In this case the camera and the drawing board could be mounted upon the upper plane surface of the girder in a similar manner as is the case for the commonly used stands of rectangular cross section.

The triangular shape of the cross section of the girder possesses the further advantage that the guides of triangular cross-section such as would otherwise be required for the carriages are not necessary as, when these carriages ride upon the girder, they are much better guided upon the inclined side faces of the girder than they would be guided by guides of triangular cross-section. The insensibility of the girder against shocks can be increased if, instead of the vertical stays *h* and rollers *i* springs are used as shown in Figs. 3 and 4. As shown in Fig. 3, rods *h* are arranged one at each end of a carrier or girder *d*. These rods *h*

are telescoped each into a foot *g*. Between the upper end of each foot and the apex of the girder a spring *f* is inserted which surrounds the upper part of rod *h* so that the carrier or girder *d* is maintained at this point in its median position with regard to the foot *g* by said spring *f*. To the lower end of rod *h* springs *s* are attached which at the other ends are attached to the foot *g* so that they stand at right angles to the vertical rod *h*.

10 In the form of construction shown in Fig. 4 two supporting springs *f* are substituted for the one spring *f* and these supporting springs are inserted between the top plate of the foot *g* and a two-armed lever *o* which is pivoted on the vertical rod *h* by a pivot pin *n*. Owing to the use of this two-armed lever *o* the unequal oscillations of the supporting springs *f* are compensated and the girder *d* is relieved from twisting stress.

I claim:-

1. A support or stand for photographic copying apparatus comprising in combination a carrier consisting of a diagonally reinforced lattice girder of triangular cross section, two feet one at each end of said girder, cushioning springs supporting said girder and acting on the same at points in the vertical planes containing the axis of the girder substantially as and for the purpose set forth, and vertical guide stays downwardly projecting from said girder and guided on said feet.

35 2. A support or stand for photographic copying apparatus comprising in combination a carrier consisting of a diagonally reinforced lattice girder of triangular cross section, two feet one at each end of said

girder, vertical springs inserted between 40 said feet and said girder, a carriage for the camera and a carriage for the drawing board, said carriages riding upon the apex of said girder, and means for securely guiding said carriages upon the inclined side 45 walls of said girder.

3. A support or stand for photographic copying apparatus comprising in combination a carrier consisting of a diagonally reinforced lattice girder of triangular cross 50 section, two feet one at each end of said girder, vertical springs inserted between said feet and said girder, a vertical stay at each end of said girder projecting into the corresponding foot, and horizontal springs 55 attached with one end to said stay and with the other end to said foot so that they stand at right angles to said stay.

4. A support or stand for photographic copying apparatus comprising in combination a carrier consisting of a diagonally reinforced lattice girder of triangular cross section, two feet one at each end of said girder, two vertical guide rods downwardly projecting one at each end of the lattice girder of triangular cross section and telescoped into the corresponding foot, a two-armed lever oscillably mounted on each guide rod near the upper end of the same, two vertical springs inserted between the 70 ends of said two-armed lever and the top end of said foot and horizontal springs one at each side of the guide rod attached with one end to said guide rod and with the other end to said foot so that springs stand at 75 right angles to said guide rod.

In testimony whereof I affix my signature
WALTER HOH
